J. R. COLGAN

LAPEL PIN OR THE LIKE

Filed Feb. 9, 1928

FIG. No. 1

FIG. No. 2

INVENTOR.

John Ralph Colgan.

Patented July 10, 1928.

Des. 75,719

UNITED STATES PATENT OFFICE.

JOHN RALPH COLGAN, OF KANSAS CITY, MISSOURI.

DESIGN FOR A LAPEL PIN OR THE LIKE.

Application filed February 9, 1928. Serial No. 25,296. Term of patent 14 years.

To all whom it may concern:

Be it known that I, JOHN RALPH COLGAN, a citizen of the United States, residing at Kansas City, in the county of Jackson and the State of Missouri, have invented a new, original, and ornamental Design for Lapel Pin or the like, of which the following is a specification, reference being had to the accompanying drawing, forming part thereof.

I claim:

The ornamental design for a lapel pin or the like, as shown.

JOHN RALPH COLGAN.
